UNITED STATES PATENT OFFICE.

EARL E. EICKMEYER AND HOWARD L. JONES, OF DAYTON, OHIO, ASSIGNORS TO THE DAYTON PUMP & MANUFACTURING COMPANY, OF DAYTON, OHIO, A CORPORATION OF OHIO.

DESIGN FOR A GASOLINE-PUMPING APPARATUS.

Application filed August 15, 1927. Serial No. 23,090. Term of patent 7 years.

To all whom it may concern:

Be it known that we, EARL E. EICKMEYER and HOWARD L. JONES, citizens of the United States, and residents of Dayton, in the county of Montgomery and State of Ohio, have invented a new and ornamental Design for Gasoline Pumping Apparatus, of which the following is a specification, reference being had to the accompanying drawing, forming a part thereof.

In the accompanying drawings:

Fig. 1 is a side elevation of a gasoline

pumping apparatus embodying our new design; and

Fig. 2 is a partial plan and sectional view, the section being taken on the line 2—2 of Fig. 1 and looking in the direction of the arrows.

We claim:

The ornamental design for a gasoline pumping apparatus, as shown.

EARL E. EICKMEYER,
HOWARD L. JONES
